UNITED STATES PATENT OFFICE.

FITZ W. SARGENT, OF MAHWAH, NEW JERSEY, ASSIGNOR TO EDWARD H. FALLOWS, OF NEW YORK, N. Y.

BRAKE-SHOE.

No. 888,751.

Specification of Letters Patent.

Patented May 26, 1908.

Application filed December 19, 1907. Serial No. 407,144.

To all whom it may concern:

Be it known that I, FITZ W. SARGENT, a citizen of the United States, and a resident of Mahwah, in the county of Bergen and State of New Jersey, have made and invented certain new and useful Improvements in Brake-Shoes, of which the following is a specification.

My invention relates to an improvement in 10 brake shoes, and more particularly to that kind or type thereof commonly known and referred to as steel back brake shoes, and to a shoe designed more especially for use upon engine driving wheels, the object of the invention being to provide a superior strengthening back for the shoe by adding rigidity not only to the body thereof, but also to the flange of the shoe which fits over and contacts with the flange of the wheel.

20 A further object of the invention is to provide a steel back for a driver shoe so formed that the end thrust of the brake head to which the shoe is attached, will be directed against integral portions of the back itself, rather than against the cast metal forming 25 the body of the shoe, whereby the effectiveness of the shoe will be increased and the danger of fracture thereof greatly lessened.

With these and other ends in view, the invention consists in certain novel features of 30 construction as will be hereinafter fully described and pointed out in the claims.

In the accompanying drawings, Figure 1 is a plan view of a driver shoe constructed in 35 accordance with my invention. Fig. 2 is a longitudinal sectional view thereof taken on the line 3—3 of Fig. 1. Fig. 3 is a view in perspective of the steel back detached from the shoe. Fig. 4 is a sectional view taken 40 on the line 4—4 of Fig. 1.

Referring to the drawings, A represents the body of the shoe preferably made of cast iron, or the same may be composite in character, that is, made of relatively hard 45 and soft metal, or soft filling, and either with or without inserts, as desired. As in the case of shoes designed for use upon the driving wheels of locomotives, the portion A¹ of the body of the shoe contacts with that portion of the tread of the wheel which is the least worn by contacting with the rail, a groove or channel A² being formed in the body of the shoe to avoid any frictional contact with that portion of the tread of the

wheel worn by the rail, said body being also 55 formed with a flange A³ adapted to fit over and contact with the flange of the wheel.

At or adjacent to the back of the shoe is located the steel back B, preferably formed of a single piece of metal and provided with 60 the openings c for the purpose of allowing the cast metal of the body of the shoe to flow through the same and securely anchor the back to the said body, the edges of said openings, as clearly illustrated in Figs. 2 and 65 4, being beveled to assist in locking the parts together. This back B is curved in the direction of its length to conform to the curvature of the body A, and at one side D thereof is also laterally curved to conform 70 to the curvature of the flange A³, over which the portion D fits, said curved flange D of the back being also provided with the openings d to allow the cast metal of the flange 75 of the shoe to flow through the same and assist in anchoring the back to the body of the shoe. In addition to the openings e formed in the plate C, and the openings e formed in the curved flange D, the back is also provided at one edge with the recesses e 80 and at its ends with the recesses f into which the cast metal of the body of the shoe flows to assist in anchoring the back thereto.

In order that the steel back may receive 85 the end thrust of the brake head (not shown), extreme ends E of the back are upwardly turned, as clearly illustrated in Figs. 2 and 3, these upturned ends being reinforced by the cast metal of the body, thereby materially 90 strengthening the completed shoe and largely 95 overcoming all danger of fracture to the cast metal which frequently occurs where the end thrust of the head is directed against the brittle cast iron ends of the body. By thus forming a steel back comprising a plate C and integral curved flange D with upturned ends E, the rigidity of the shoe is greatly increased, and the danger of fracture materially 100 lessened, the integral curved flange D operating to materially strengthen and stiffen the back, as well as adding stiffness to the shoe itself.

For the purpose of attaching the shoe to the 105 brake head, a hole or opening F is formed through the body of the shoe, and through the back B, near one end thereof, and through which passes a bolt ordinarily used for the purpose, the opposite end of the shoe

being provided with a hook G, the ends g thereof being securely anchored in the body of the shoe.

Having fully described my invention, what I claim as new and desire to secure by Letters Patent, is:

1. A steel back for a brake shoe, comprising a plate curved in its length and formed at one side thereof with a curved flange, the ends of said plate being upwardly turned to receive the end thrust of the brake head, substantially as described.

2. A brake shoe consisting of a body and a plate located at or adjacent to the back thereof, said plate being perforated and having its ends turned upwardly to receive the end thrust of the brake head, substantially as described.

3. A brake shoe provided with a steel back located at or adjacent to the back of the shoe, said steel back comprising a perforated plate formed with an integral curved flange, the ends of said plate being turned upwardly to

receive the end thrust of the brake head, substantially as described.

4. A brake shoe comprising a body and a steel back located at or adjacent to the back of the shoe, said steel back being formed with a perforated plate and with an integral perforated curved flange, the ends of said plate being turned to receive the end thrust of the brake head, substantially as described.

5. A brake shoe comprising a body and a steel back located at or adjacent to the back of the shoe, said steel back being formed of a perforated plate and an integral curved perforated flange, the ends of said plate being upwardly turned and reinforced by the cast metal of the body, substantially as described.

Signed at Mahwah in the county of Bergen and State of New Jersey, this 14th day of Dec. A. D. 1907.

FITZ W. SARGENT
